UNITED STATES PATENT OFFICE.

NATHANIEL B. SHELDON, OF ROCHESTER, NEW YORK.

CAR-COUPING.

SPECIFICATION forming part of Letters Patent No. 296,233, dated April 1, 1884.

Application filed October 20, 1883. (No model.)

To all whom it may concern:

Be it known that I, NATHANIEL B. SHELDON, a citizen of the United States, residing at Rochester, in the county of Monroe and State 5 of New York, have invented certain new and useful Improvements in Car-Couplings; and I do declare the following to be a full, clear, and exact description of the invention, such as will enable others skilled in the art to which 10 it appertains to make and use the same, reference being had to the accompanying drawings, and to the letters and figures of reference marked thereon, which form a part of this specification.

15 This invention relates to that class of inventions known as "automatic car-couplings," the object of my invention being to provide a coupler which shall be readily coupled and uncoupled without danger to the operator, 20 which shall be strong and durable in practice, and effective and efficient in operation; and it consists of the construction, combination, and arrangement of parts, as will be hereinafter more fully explained, and particularly pointed 25 out in the claims.

Referring to the drawings which form a part of this specification, and in which like letters of reference indicate like parts in all the figures, Figure 1 is a front view of a car 30 provided with my improved coupler and means for uncoupling the same. Fig. 2 is a longitudinal section. Fig. 3 is a plan view with the top plate removed, and Figs. 4, 5, and 6 are details.

35 In carrying out my invention I employ two side plates, A, to the top and bottom of which are secured the plates B B by suitable screws or bolts. The plates A are provided with grooves a, into which the rear plate, a', is placed, and secured by screws or bolts which pass through the side plate, A, and into or 40 through said end plate, which are also provided with longitudinal grooves in line with grooves a', made in a rib which extends in-

45 wardly from each of the sides of the plates A. Into the grooves of said end plate, a', are inserted the rear ends of the spring-plates, the ends of said spring-plates having bearings in the grooves a'. At the rear of the draw-head

50 in the plate a' is an aperture, which passes a spring-bolt, the rear end of which fits in an aperture, c, in the block C, the forward end

of which serves as a bearing for an end of a spring, c', the opposite end acting upon a collar. The forward end of said bolt or bar E 55 has transverse grooves a', as shown. To the upper end of the grooved bar is secured a plate, D, which is bifurcated at its forward end, and is adapted to slide backward and forward over a slot in the upper spring-plate. 60 The draw-head is provided with a tube, d, to assist in holding the coupling-pin in an upright position while resting upon the sliding plate D. When the pin is withdrawn, the bar E is pushed forward, carrying the plate D, 65 which covers the longitudinal slot a' in the plate b. The coupling-link passes into either one of the chambers formed by the spring-plates, and thence strikes the bar E, setting into one of the grooves a' therein, pushing it 70 back until the slide D passes from under the pin D', permitting the latter to drop.

It will be understood that the spring-plates will yield if acted upon by a link which stands obliquely to the longitudinal axes of the buffers. 75

Any well-known means for raising the coupling-pin may be employed. I prefer, however, the one shown, in which a pin can be raised from the top or either side of a car. 80

I am aware that a series of plates have been placed in a draw-head, the inner ends being separated by rubber blocks.

I am aware that changes in the form and construction of parts herein described can be 85 made without departing from the principle or sacrificing the advantages of my invention—as, for instance, the number of spring-plates can be changed, the sliding plate not bifurcated, &c. I would therefore have it understood that I do not limit myself to the exact construction shown and described, but hold myself at liberty to make such changes as fairly fall within the scope of my invention. 90

What I claim is—

1. A draw-head having the side pieces, A, provided with grooves a a', in combination with the end piece, a', fitted in the groove a, and spring-plates b, as and for the purpose set forth. 95

2. A series of spring-plates, b, having slots for the passage of the coupling-pin, and rigidly secured to the end plates, a', and having their edges bearing in grooves which pass 100

transversely through vertical ribs in the draw-head, as set forth.

3. The bar E, having a series of transverse grooves, a^4 , in combination with the spring-bolt, perforated plate a' , and spring-plates, as and for the purpose set forth.

4. The combination of a series of slotted spring-plates with the bar E, having a sliding piece at its upper end, and a series of transverse grooves, a^4 , arranged centrally between

said plates, spring-bolt c' , coupling-pin, and means for raising the latter, as and for the purpose set forth.

In testimony whereof I affix my signature in presence of two witnesses.

NATHANIEL B. SHELDON.
